UNITED STATES PATENT OFFICE.

WILLIAM A. INGALLS, OF PROVIDENCE, RHODE ISLAND, ASSIGNOR OF ONE-HALF TO GEORGE E. BARSTOW, ASA LYMAN, AND DANIEL T. LYMAN, ALL OF SAME PLACE.

SAFETY-GUARD FOR ELEVATORS.

SPECIFICATION forming part of Letters Patent No. 289,350, dated November 27, 1883,

Application filed March 14, 1883. (No model.)

To all whom it may concern:

Be it known that I, WILLIAM A. INGALLS, of Providence, in the State of Rhode Island, have invented an Improvement in Safety-Guards for the Shafts of Elevators, of which the following is a specification.

My invention relates to that class of elevator safety-guards which are made of flexible material and are attached at one end to the elevator-car, so as to move therewith and cover the door-openings above and below the car; and it consists in the improved construction and arrangement of the flexible safety-guard and its attachments, as hereinafter fully set forth.

Figure 1 is a front elevation of the elevator-shaft. Fig. 2 is a central vertical section taken in the line *z z* of Fig. 1. Fig. 3 is a vertical section taken in the line *w w* of Fig. 1. Fig. 4 is a transverse section taken in the line *x x* of Fig. 1. Figs. 5, 6, 7, and 8 are detail views.

In the drawings, A is the elevator-shaft. B is the elevator-car. C is the hoisting-rope, passing over the pulley D and thence to the drum E at the bottom of the elevator-shaft. To the upper front corner of the car B is attached the safety-guard F, formed of a flexible canvas apron, *f*, upon the front surface of which, at suitable intervals, are placed the transverse bars *g g*, which serve to support and stiffen the apron transversely without interfering with its longitudinal flexibility. To the lower front corner of the car B is attached the flexible canvass apron *f'*, also having attached to its front surface the transverse bars *g g*, and the opposite edges of the aprons *f f'* are made to pass up and down within the groove *e* of the guides G G, which are arranged vertically in the elevator-shaft at each side of the door-openings H H, as shown in the transverse section, Fig. 4. At the upper and lower ends of the grooved guides G G, for the passage of the safety-guard F, are placed the guiding-rolls I I', which serve to direct the safety-guard into the groove of the guides G G, to follow the movement of the car either in

rising or falling, and the rolls I I' thus allow the safety-guard to be deflected, as required, at the ends of the elevator-shaft without obstructing the free and direct entrance of the guard into the guiding-grooves *e e*. Above the guide-roll, Figs. 2 and 3, is placed the roll J, for winding up the apron *f*, or that portion of the safety-guard F which lies above the car B, and the roll J is actuated to wind up the apron *f* by means of the rope K and weight L, the rope K becoming wound up on the roll J when the car B descends in the shaft, and unwinding from the same when the car takes an ascending movement. Below the guide-roll I, Figs. 2 and 3, at the lower end of the shaft, is placed the roll J', for winding up that portion of the safety-guard F that lies below the car B; and the roll J' is actuated in its winding-up movement by means of the rope K', which passes from the roll J' under the pulley M, thence to the top of the shaft and over the pulley N, and downward to the weight L', the rope K' becoming wound up on the roll J' when the car ascends in the shaft, and unwinding from the same when the car takes a descending movement.

The bars *g g*, attached to the apron *f*, may be made of wood, and provided with a central groove, *h*, into which is placed a metallic bar or sheet-metal strip, *i*, edgewise, as shown in the transverse section of the bar, Fig. 8, and in the vertical view and partial section, Fig. 7, the bar *g* being attached to the canvas apron *f* by means of screws *j j* or by suitable cement. The apron *f* may be divided longitudinally at the lines *k k*, and transversely on the line *m m* both above and below the car B, in order to secure ready access to the interior of the elevator-shaft by moving the flap *n* inward, as shown in Fig. 6; and when in its closed condition the angularly-divided bars *g g* are secured to each other by means of suitable pins, *o*, Fig. 8, which enter the holes *p p*, shown in Fig. 7, thus locking the parts again firmly to each other. The safety-guard F may be lettered and notated, as shown in Fig. 1, in order to indicate the position of the

car in the shaft at each of the several floors, and upon the arrival of the car at any one of the doors of the shaft A, the position of the car at that moment will be indicated at the doors of each of the other floors, whether above or below.

I do not of course limit my claim to the specific lettering and notation shown in the drawings, Fig. 1, but include any form of marking, lettering, or notation which, when printed, stamped, marked, or attached to the safety-guard F, will serve to convey the desired information regarding the position of the car.

15. I claim as my invention—

1. The combination of the apron f, provided with the transverse bars g g, with the elevator-car B, the grooved guides G G at opposite sides of the door-openings, roll J, adapted 20 for rolling up the apron f, the intermediate guide-roll, I, adapted to guide the apron f into the grooves of the guides G G from the rolled-up portion of the apron upon the roll J, rope K, and weight L, substantially as described.

25. 2. The combination of the elevator-car B, the grooved side guides, G G, apron f', pro-

vided with the transverse bars g g, roll J', adapted for rolling up the apron f', guide-roll I', adapted to guide the apron f' into the grooves of the guides G G from the rolled-up 30 portion of the apron upon the roll J', rope K', pulleys M and N, and weight L', substantially as described.

3. The combination of the elevator-car with the safety-guard, provided with a swinging 35 door, formed from the material of the safety-guard, and moving with the car, substantially as described.

4. In a safety-guard for the shaft of an elevator, the transversely-arranged wooden bars, 40 provided with the metallic strengthening-piece arranged edgewise in the wooden bar, substantially as described.

5. The safety-guard, arranged to move up and down with the movement of the elevator-car, and marked or notated to indicate the position of the elevator-car in the shaft, substantially as described.

WILLIAM A. INGALLS.
